CANE OR UMBRELLA HANDLE.

No. 20,146.

Patented Sept. 9, 1890.

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,146, dated September 9, 1890.

Application filed July 31, 1890. Serial No. 880,674. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Cane, Umbrella, or Parasol Handles; and I do hereby declare the following to be a full, clear, and exact description of the invention, such as will enable others skilled in the art to 5 which it pertains to make and use it, reference being had to the accompanying drawing, which forms part of this specification.

My invention relates to an improvement in designs for cane, umbrella, or parasol handles; and it consists in the novel shape and configuration of parts, whereby a pleasing and beautiful effect is produced, as will be more fully described hereinafter.

The accompanying photographic illustration represents my invention.

A represents the main portion of the handle, which has its outer end bent or shaped as shown, and upon the outer end of which are formed ornamental volutes C. Through 25 this handle there are made two openings D, one above the other, and clinging to the handle is the figure of an animal or monsther G, whose body passes through the two openings and has its tail wound around the inner end of the handle, as shown. The animal or 30 monsther is provided with claws, and extending from opposite sides of the animal's mouth are whiskers, as shown. The head is represented as having grasped hold of the handle as if to bite it.

A handle constructed as here shown and described presents a very novel and attractive appearance and adds greatly to the article to which it is applied.

Having thus described my invention, I 40 claim—

A design for a cane, parasol, or umbrella handle, substantially as herein shown and described.

In testimony whereof I affix my signature in 45 presence of two witnesses.

ALBERT ROSENSTEIN.
